UNITED STATES PATENT OFFICE.

CHARLES BURNHAM, OF LOS ANGELES, CALIFORNIA, ASSIGNOR TO BURNHAM BASKET COMPANY, A CORPORATION OF CALIFORNIA.

BOX-MAKING MACHINE.

1,252,545.

Specification of Letters Patent. Patented Jan. 8, 1918.

Application filed June 22, 1915. Serial No. 35,702.

To all whom it may concern:

Be it known that I, CHARLES BURNHAM, a citizen of the United States, and a resident of Los Angeles, county of Los Angeles, 5 and State of California, have invented certain new and useful Improvements in Box-Making Machines, of which the following is a full, clear, and exact description.

This invention relates more particularly 10 to the mechanism for bending metal strips to form a binding for fruit and berry boxes or baskets.

One of the principal objects of the invention is to provide simple and efficient means 15 adapted to receive a thin narrow metal strip or strips at either or both sides thereof and to fold said strips about an anvil or former to form a binding for the body of the baskets or boxes.

Another object of the invention is to provide simple and efficient means whereby the 20 parts will register properly, and to provide an adjustable two-part frame on which the folding mechanism may be mounted.

A further object of the invention is to provide simple and efficient means which 25 will permit narrow strips folded lengthwise to be fed from opposite sides of the folding mechanism and by said mechanism moved 30 against a substantially rectangular anvil or former and folded about said former on all sides thereof for the reception of the edge of the box body.

Other objects of the invention are to provide 35 simple and efficient means forming a back stop for a part of the folding mechanism; to provide simple and efficient folding jaws or members and means for operating the same; to provide simple means 40 whereby the long strips may be cut off at either or both sides of the folding mechanism, and to provide simple means whereby certain of the folding jaws may be moved to a position so as not to interfere with 45 the movement of the metal binding as it is forced about the anvil by other of the folding jaws.

A still further object of the invention is to provide simple and efficient means for retaining 50 the metal binding strip or strips in the initial folding jaws.

With these and other objects in view, the invention will be hereinafter more particu-

larly described with reference to the accompanying drawings, which form a part of 55 this specification, and will then be pointed out in the claims at the end of the description.

In the drawings, Figure 1 is a sectional plan view of one form of folding mechanism embodying my invention.

Fig. 2 is an end elevation, partly in section, showing one member of the two-part supporting frame, and the cutting means at 60 one side of the machine.

Fig. 3 is a transverse section taken on the line III—III of Fig. 1, the anvil being omitted and the rear portions of the machine being broken away.

Fig. 4 is a front elevation, partly broken 70 away, looking from the lanner side of the folding mechanism.

Fig. 5 is a vertical section taken on the line V—V of Fig. 1, the anvil being omitted and other parts broken away for the sake 75 of clearness.

Fig. 6 is an enlarged fragmentary sectional plan showing a part of the anvil and one of the lanner jaws in its normal position.

Fig. 7 is a fragmentary vertical section 80 taken on the line VII—VII of Fig. 6.

Fig. 8 is a front view of the mechanism shown in Figs. 6 and 7 looking into the mouth or face of the folding lanner jaw.

Fig. 9 is a plan view similar to Fig. 6 85 showing the opposite lanner jaw in its normal position.

Fig. 10 is a vertical section taken on the line X—X of Fig. 9.

Fig. 11 is an enlarged front view looking 90 into the mouth of the lanner jaw shown in Fig. 10.

Fig. 12 is an enlarged vertical section through one of the initial folding jaws showing the retaining shutter in position, 95 the section being taken on the line XII—XII of Fig. 1.

Fig. 13 is an enlarged vertical section on the line XIII—XIII of Fig. 1 through one of the retaining fingers for holding the binding in the initial folding jaws during the movement of the jaws toward the anvil.

Fig. 14 is an enlarged sectional plan of the center bar of the initial folding means showing one means whereby the ends of two 105 strips when fed from opposite sides of the

machine may be made to overlap, the section being taken on the line XIV—XIV of Fig. 15; and

Fig. 15 is a section taken on the line 5 XV—XV of Fig. 14.

While the invention shown is applied to a particular form of machine such as disclosed in my Patent No. 1,154,610 issued September 28, 1915, it will be understood 10 that many of the features may be used in connection with other forms of machines and that some of the parts may be dispensed with or others substituted therefor, or the invention may be adapted for use in connection with a machine which is partly automatic or which is operated by hand.

In the general operation of a basket or box-making machine to which this invention is particularly applicable, a metallic strip 20 is fed from a reel or otherwise suitably supported convenient to the machine, and this strip by suitable mechanism is fed to what I term forming mechanism, that is the metal is bent or formed lengthwise thereof so as 25 to be substantially V-shaped or U-shaped in cross-section in order to fit over the edge of the box form. This strip is fed inward and tilted and after being tilted so that it will assume a proper position relative to the edges of the box and the anvil or former, 30 about which it is bent according to the shape of the box, the strip is then cut off the proper length. The strip is then fed forward on one side of a substantially rectangular anvil having a shape corresponding 35 to the shape of the open end of the box and until the said strip meets the anvil, when the jaws into which the strip has been previously fed by engagement with the former or anvil will bend both ends of the strip on opposite sides thereof making the same substantially U-shaped. A second pair 40 of jaws engages the free ends of the binding strip and forces the same on the remaining side of the anvil and causes one end of the strip to overlap the other. The shooks of 45 which the box body is made are placed in two magazines located adjacent to one end of the machine, and these shooks are automatically fed upward in position to be removed therefrom. A reciprocatory and rotary pneumatic device is provided for this 50 purpose and this device is automatically controlled so that the shooks will be picked up first from one magazine and then from the other so that the shooks as thus picked up will lie crosswise and at substantially right angles to each other. The pneumatic devices discharge the crossed shooks into a 55 rotary carrier or turret. A movement is given to the carrier and this places the crossed shooks in the path of box-making mechanism, and at the proper time this mechanism operates to form the shooks into 60 box form and carries the box from above

the carrier and forces the upper edge thereof into the binding strip. The binding strip is then pinched on to the shooks thus holding the box shooks permanently together in box form. Mechanism is provided for stripping the box and causing the completed box to be deposited into the carrier, and the carrier as it feeds new shooks crosswise to the die mechanism conveys the completed box into position to be discharged. The completed box is forced out of the carrier into a chute and properly stacked and may be removed in any desired way. This is the character of machine disclosed in the application referred to. Broadly the metal 75 binding, folding or bending mechanism shown in the present application is constructed to adapt metal strips to be fed endwise from both sides and there are two cutting off mechanisms when the strips are 80 long, though it is intended that the invention may be used when the metal binding strip or strips are fed from one side only of the folding mechanism and each binding 85 consists of a single piece instead of a plurality of pieces.

The frame of the machine may have a drop head bracket or support 10 of any desired construction fastened in any suitable manner (not shown) to a fixture and supported by said bracket are folder frame members or brackets 11 and 12. These frame members 11 and 12 have a substantially T-shaped slot 13 along the upper edge thereof and adapted to fit into each slot is 90 a bar 14. The bar 14 is adapted to be engaged by the threaded ends of two or more bolts 15 and by said bolts 15 and bars 14, the said frame members 11 and 12 may be adjustably or otherwise held to the supporting member 10. At each lower inner edge or face of the members 11 and 12 are guides 16. These guides are opposed to each other and adapted to reciprocate transversely of the machine is a folder cross-head 17. This 95 cross-head 17 carries the initial folding jaws 18 and 19 each of which is pivoted, at 20, to a center bar or member 21. The jaws 18 and 19 and bar 21 in their normal position are in alinement and both the jaws and the member 21 have a bar-like part 22, the outer 100 face of which is provided with a groove 23 for the reception of the metal binding 23a. The metal binding strip may be fed to the jaws endwise in any desired way, and said 105 strip or strips before being received by the jaws is substantially U-shaped or V-shaped in cross-section and when in position and held by the jaws, has one side thereof substantially vertical, it having been previously 110 tilted and placed in this position if the machine is constructed to fold the strip lengthwise in the manner substantially set forth in the patent hereinbefore referred to. The jaws 18 and 19 extend in opposite directions 115

from the center member 21 and are adapted to reciprocate with said member 21 and with the cross-head 17, and during the reciprocatory movement of the cross-head, the 5 member 21 is adapted to move against the side 24 of an anvil or former 25. This anvil or former is substantially rectangular in form having sides 25^a and a fourth side 25^b in addition to the side 24, and said anvil has 10 corner pieces 26 and parts 27 at the corners forming sockets which are adapted to be engaged by recessed portions 27^a located above the pivot 20 of the jaws 18 and 19. As the cross-head 17 continues to move after the 15 member 21 engages the side 24 of the anvil, the engagement of the recessed or socket portions 27^a with the parts or posts 27 will cause the jaws 18 and 19 to swing about the sides 25^a of said anvil. The jaws 18 and 19 20 are pivoted, at 28, to levers 29. These levers 29 are pivoted, at 30, to a part of the cross-head 17. The levers 29 at their outer portions are provided with guide flanges 32 which are adapted to be engaged by rollers 25 33 held upon the ends of adjustable bars or plates 34, the latter being held to the frame members 11 and 12 by means of bolts 35 and by set screws 36, the said rollers serving as 30 guide means for the levers 29 during the reciprocation of the cross-head 17. A lug or pin 37 extends outwardly from each jaw 18 and 19 and connected to said pin is one end of a spring 38, the other end of said spring being connected to the outer end of a bracket 35 39 secured to a part of the cross-head 17 and serving normally to hold each of the jaws 18 and 19 when in their normal position in alignment with the center member 21 and so that the back of each jaw will rest and 40 abut against a stop 40 formed as a part of each lever 29.

It will be evident that as the cross-head 17 is moved toward the anvil or former 25, the sockets 27^a at the pivots 20 of the jaws 45 will engage the socket pieces 27 of the anvil and as the cross-head continues to move forward, the member 21 will remain against the side 24 of the anvil 25 and the jaws 18 and 19 will move about the opposite sides 50 25^a and at right angles to the member 21 so as to fold the strip or strips carried thereby about the two sides 25^a of the anvil 25. During the swinging movement of the jaws 18 and 19, the lever members 29 will move on 55 their pivots against the tension of the springs 38, this connection being necessary because of the arc of movement of the pivots 28. As the cross-head moves backward to its normal position, the member 21 as well as the 60 jaws 18 and 19 will also be moved backward and owing to the tension of the springs will be restored to alignment. At the extreme back movement of the member 21, a substantially U-shaped part 41 held to the center 65 member 21 will engage a stop 42. This stop

42 is in the form of a screw which is adjustably held to the lower end of an arm or bracket 43 extending downward from the main supporting frame or bracket 10, the purpose of said stop being to assist in aligning the member 21 with respect to the jaws 18 and 19 for the reception of the metal binding strips to be bent. Stops 41^a in the form of bolts may also be provided to engage parts of the cross-head 17 when in its 70 extreme backward position.

The cross-head 17 may be reciprocated in any desired way. It may be timed with respect to other parts of the machine if the mechanism is to be used in connection with 80 a machine partly or wholly automatic. Only a part of such mechanism is shown. This mechanism may comprise rods 42^a and 43^a which are pivoted, at 44, to lugs or other parts of the cross-head 17 and at their outer 85 ends the rods 42^a and 43^a may each have a head 45 to which is pivoted, at 46, one end of rocking levers 47. The compression rods 42^a and 43^a may have a compression washer 46^a on each rod and on each side of the rubber 90 washer is a steel washer, one washer resting against the forward end of the head 45 and the other against the two lock nuts 46^b, and inside each head or block 45 is a compression spring and two round lock nuts, which 95 latter it was not thought necessary to illustrate. When the levers 47 are moved they will positively force the cross-head 17 with the jaws 18 and 19 toward and from the 100 anvil 25.

Each metal binding when completed may be made of a single strip of metal or a plurality of strips. If the strip consists of a single piece or a plurality of pieces, it is fed endwise from one side of the machine 105 entering either one of the jaws 18 and 19 endwise thereof so as to extend on opposite sides of said jaws. If the binding comprises two strips for example, the separate strips may be fed in any desired way from opposite 110 sides of the mechanism so that one strip will enter endwise the jaw 19 and the other strip enter endwise the jaw 18 so that they will slightly overlap at the center of the center member 21. At this time and before the 115 cross-head 17 is reciprocated, the strip or strips are held in the jaws against displacement by means of a shutter 48. This shutter 48 is in the form of a beam and is arranged over and in parallel relation with the jaws 120 18 and 19. The shutter 48 has a lip portion 49 which is adapted to cover the front or open portion of the groove 23 extending along the face of the jaws and the center member 21 and at its ends is pivoted, at 50, 125 to lugs or bosses on the folder frame members 11 and 12. This shutter is operatively connected to one or more arms 51, the outer ends of which are connected to a rod 52 so that on the operation of said rod 52, the 130

shutter may be moved on its pivot and be free of the jaws 18 and 19 and center bar 21. The shutter is moved just prior to the reciprocatory movement of the cross-head 17 and does not partake of such reciprocatory movement. A pair of fingers 53, one for each jaw, is adapted to hold the strip or strips in the jaws 18 and 19 during the reciprocatory movement of the cross-head 17 and until the jaws move about the anvil 25. These fingers 53 extend vertically and are pivoted, at 54, to a part of the cross-head and move therewith. The fingers 53 are each normally forced in one direction to hold the strips in the grooves of the jaws by means of a spring 55 arranged around a rod 55^a, one end of which rod is pivotally attached to one end of the finger and the other end of said rod passes through an opening in a lug 56 in the cross-head 17. As the cross-head is moved forward and just before the jaws 18 and 19 move on their pivots to force the binding about the two sides 25^a of the anvil 25, the said fingers are released by engagement of the lower end thereof with a cam portion 57 of fixed brackets 58 secured to the frame members 11 and 12 on opposite sides of the anvil 25.

As the metal binding is forced about the anvil, the free ends of the binding on opposite sides of the anvil 25 during the swinging movements of the jaws 18 and 19, pass over curved guides 59 on opposite sides of the anvil and over a fixed projecting member 60 which forms a continuation of each guide 59, said member 60 having an inwardly projecting part which overlaps a part of the lapper mechanism in such a way as to prevent the said mechanism from interfering with the free swinging movement of the free ends of the binding metal. The lapper mechanism comprises two oppositely movable sections 61 and 62 which are opposed to each other and move at right angles to the direction of movement of the cross-head 17 and are adapted to force the free ends of the metal binding about the remaining side 25^b of the anvil 25 and to cause said ends of the binding to overlap. Except for the construction of the bending jaws of the lapper mechanism sections 61 and 62, they are substantially identical in construction and operate in substantially the same manner and the description of one will answer for the description of the other except as to the special construction of the jaws which will be referred to later. The jaw 63 of the lapper section or mechanism 61 has a socket portion 64 which is adapted to engage a socket pin or part 65 on the anvil 25 to move about the same when forced inwardly. This jaw 63 is provided with a grooved bar 66 which is adapted to receive the free end of the strip or metal binding which has been forced around the anvil by the jaw 19. The jaw 63

is pivoted, at 67, to a pivotally held member 68 and is held at substantially right angles to its direction of reciprocatory movement and with respect to the member 68 by a spring 69, one end of said spring 70 being held to one end of a projecting arm 70 and the other end of said spring being held to a link 71 on the jaw 63. The member 68 is pivotally held, at 72, to a rocking supporting member 73. This member 73 is held to rock on a horizontally arranged stud or shaft 74 extending transversely of a reciprocatory cross-head or slide 75. The member 73 is provided with a lug or tooth 76 which is adapted normally to engage a tooth 77 or projecting part 77 on the member 68. The teeth or projections 76 and 77 are held normally in engagement by means of a torsion spring 78, one end of which is held to a lug 79 on the rocking member 73 and the other end to an adjustable nut or part 80 and by which the tension of the spring 78 may be varied. An arm 81 extends outwardly from and forms a part of the member 73 and said arm is provided with a trundle which is adapted to enter a cam groove 82 in a block or fixed part 83. The normal position of the jaw 63 is that shown in the drawings. The arm 81 is caused to tilt the member 73 and jaw 63 to the position shown in order that the free end of the strip while being forced about the anvil by the jaw 19, may pass over the guiding ledges 59 and 60 in advance of the jaw 63 so that when the slide 75 is advanced, the trundle in passing along the cam groove 82, will raise the jaw 63 to a substantially horizontal position and in alignment with the free end of the metal binding or strip so that said binding or strip may enter the groove 66 of said jaw 105 and be carried by the jaw as the latter with its slide 75 is forced inward. As soon as the socket portion 64 engages the socket pin or part 65 of the anvil 25, the jaw 63 will swing about the anvil 25. Owing to the arc of movement of the pivot 67 of the jaw and the connection between the said pivot and the pivot 72, the tooth 76 will be moved away from the lug or projection 77 against the tension of the spring 78, and during the continued inward movement of the jaw and the slide 75 will force the binding metal about the remaining side of the anvil 25, the spring 69 serving to keep the socket 64 in engagement with the part 65 on the anvil and to return the jaw 63 to its normal position. The slide 75 may be of any suitable construction and is properly guided in the frame members 11 and 12 and may be provided with a transversely extending pin or stud 84 to 125 which a rod 85 is connected, said rod 85 being operated by a cam or in any other suitable manner and timed with relation to the movement of the jaws 18 and 19.

The construction of the section or mecha- 130

nism 62 differs from the section 61 and from that described only in one feature. The jaw 86 of said mechanism has a pivotally held part or member 87 by which the 5 end of the metal binding operated on by said jaw during the reciprocatory movement of the slide 75 of said mechanism is adapted to move the strip downward far enough to pass under the previously bent strip end in 10 order that the two ends may overlap and thus form a substantially continuous rectangular binding about the anvil 25. The jaw 86 has a socket piece 88 adapted to engage a pin or socket part 89 of the anvil 25 15 similar to the socket portion 64 of the jaw 63 and has the movable member or part 87 pivotally held thereto, as at 90, under said socket piece 88. The jaw member 87 is provided with a grooved bar 91 for the reception 20 of the metal strip or binding. At its outer end the member 87 has a lug 91^a which is adapted to span a stud or bolt 92 extending downward from the jaw 86. A spring 93 is arranged around the rod or stud 92 and 25 at the lower end of said stud is a nut 94 by which the tension of the spring 93 may be varied. The member 87 has a tongue-and-groove connection, as at 95, with the jaw 86 and is adapted to have its outer end forced 30 downward during the reciprocatory movement of the jaw 86 with its slide 75 against the tension of the spring 93 and when again freed, the spring 93 will force the member 87 upward again so as to carry the free end 35 of the strip as it is bent about the remaining side of the anvil 25 under the free end of the strip which has been bent about the anvil by the jaw 63. This downward movement of the member 87 may be accomplished by 40 means of a cam portion 96, Fig. 1, which is carried by a part of the clencher mechanism, not shown, and which forms no part of this invention. This cam 96 is normally in the path of the reciprocatory movement of the 45 slide 75 and a part of the movable member 87 of the jaw 86 during its swinging action about the anvil 25 and serves during the swinging movement of the jaw 86 about the anvil to force the member 87 relatively to 50 the rest of the jaw and to carry the binding strip therewith. After the binding has been bent about the anvil 25 and the free ends made to overlap, the said overlapped ends of the binding may be engaged by one or more 55 devices 97 usually two, one of which at least is in the form of a movable hook and both of which are carried by the anvil or otherwise to hold the binding in position to receive the box body which may be formed in 60 substantially the same manner as disclosed in the patent referred to or in any other desired way.

The strips forming the metal binding may be fed automatically either in the form of a 65 long strip which would have to be cut off

the proper length or in the form of strips of the desired length and said strips may be fed from one side of the machine if of a length to form a complete binding or from opposite sides of the machine if the complete binding when made is to comprise two strips or sections. When the strips are fed as long strips which have been bent substantially U-shaped in cross-section and from opposite sides of the machine, cutting 70 mechanisms, as 98, Figs. 1 and 2, may be provided. As shown, there is a mechanism 98 mounted on each of the supporting frame members 11 and 12 and each mechanism is similarly constructed. The folded metal is 80 fed into the machine at an angle so that one side, that is the side next adjacent to the anvil, will be substantially vertical, the metal having been tilted by rolls or in any other desired way for this purpose. Each 85 mechanism 98 has a head 99 carrying one cutter member and a head or arm 100 carrying another cutter member. These heads or arms 99 and 100 are pivoted, at 101, to a lug or lugs extending upwardly from a frame 90 member 102, the latter being held by bolts 103 or otherwise to the under surface of each of the frame members 11 and 12. The arm 99 is connected to an arm 104 and the cutter arm 100 to an arm 105, each thereby forming 95 a bell-crank member. The arms 104 and 105 are connected by links 106 to a vertically reciprocating rod 107 forming with the links a toggle joint connection. As the rod 107 is reciprocated by a cam or otherwise, the cutter arms 99 and 100 are forced toward each other and will sever the metal binding, the said arms 99 and 100 being also provided with means, if desired, whereby one of the ends only of the metal strip may 105 be reformed by expanding or narrowing to fit over or inside of the other end in order that when the ends overlap, the overlapped portions may lie substantially flush. The cutting mechanism is not shown in detail 110 being substantially the same as disclosed in my Patent No. 1,119,340, dated December 1, 1914, and may be of any desired construction.

The construction and operation of the invention will be readily understood from the foregoing description when taken in connection with the accompanying drawings. The metal binding in the form of a strip or strips having been fed into the jaws 18 and 19 115 and the cross-head 17 reciprocated, the metal binding will be carried by the jaws 18 and 19 and center member 21 against the anvil and will be folded by the movement of the jaws 18 and 19 about three sides of said anvil. At 120 this time, the jaws 63 and 86 are rocked to a tilted position so that the free ends of the binding may pass along the guides 59 and 60 over the overlapping mechanism in position to be engaged by the jaws 63 and 86. 130

These jaws 63 and 86 are given a reciprocatory movement toward the anvil one slightly in advance of the other and during such reciprocatory movement the binding will be 5 bent about the remaining side of the anvil and one end of the binding made to overlap the other as already described.

The ends of the binding 23^a when fed from opposite sides of the machine have 10 their inner ends made to overlap, and if reformed only one of the overlapped ends is thus shaped. As one means, Figs. 14 and 15, the guide groove in the center bar 21 is made somewhat higher for one piece of the binding than for the other piece. The purpose 15 of this is to cause one end of one piece of the binding substantially central of the bar 21 to be raised far enough above the other end to be guided into said end of the other piece of 20 binding to cause the ends to overlap without liability of the ends striking against each other. Any other means than that shown may be employed to cause the inner ends of 25 the binding to overlap. The binding while 30 in the central bar 21 may be held during the reciprocation of the cross-head 17 toward the anvil by a pivoted hook or finger 108, Fig. 1, which may be released by a cam on one of the clencher jaws, the shutter bar 48 35 being constructed or cut away so as not to interfere with said finger. A hook 109 is provided on the anvil to engage the overlapped ends of the binding; and the anvil is cut away at 109^a to permit the finger 108 to move with the cross-head 17 and until the 40 binding rests against the side of the anvil. The finger 108 and the hooks 97 and 109 may be substantially the same in construction and operation as those disclosed in my application Sr. No. 15,252, filed March 18, 1915, 45 being adapted to hold the binding while the cross-head 17 is being reciprocated, after which they are moved to release said binding.

45 From the foregoing, it will be evident that effective means is provided whereby a metal binding for fruit baskets or boxes may be made from a single strip or a plurality of strips; that simple means is provided where- 50 by the action of the folding jaws may be positively controlled; that simple means is provided for mounting and supporting the folding mechanism to adapt the latter to be adjusted or removed from other parts of the 55 machine; and that the mechanism described herein is adapted for use in connection with various forms of box or basket making machines.

Having thus described my invention, I 60 claim as new and desire to secure by Letters Patent:—

1. In a box-making machine, the combina- 65 tion of a rectangular anvil, a reciprocatory cross-head, two jaws pivotally mounted on said cross-head and adapted with said cross-

head to force metal binding about three sides of the anvil, cutting mechanism ar- 70 ranged on opposite sides of the jaws, means for initially holding the metal binding in said jaws, pivotally held fingers movable with the jaws and adapted to hold the binding in the jaws during the reciprocatory movement thereof, means for automatically releasing the fingers, and lapper mechanism 75 having two jaws movable toward and from each other and at right angles to the movement of the first-mentioned jaws and adapted to bend the metal binding on the remaining side of the anvil, one of said jaws being provided with a member having an up-and-down movement adapted to cause the ends of the binding metal to overlap.

2. In a box-making machine, the combina- 80 tion of a rectangular anvil, a reciprocatory cross-head, two jaws mounted on said cross-head and adapted to force metal binding about a part of the anvil, cutting mechanism, 85 means whereby metal binding strips may be fed endwise into the jaws to be held thereby, means for initially holding the metal bind- 90 ing in said jaws, pivotally held fingers movable with the jaws and adapted to hold the binding in the jaws during the reciprocatory movement thereof, means for automatically releasing the fingers, and lapper mechanism 95 having two jaws movable toward and from each other and at right angles to the movement of the first-mentioned jaws and adapted to bend the metal binding about the rest of the anvil, one of said jaws being provided with a member having an up-and-down movement adapted to cause the ends of the 100 binding metal to overlap.

3. In a box-making machine, the combina- 105 tion of a rectangular anvil, two pivotally held jaws adapted to force metal binding about a part of the anvil, pivotally held fingers movable with the jaws and adapted to hold the binding in the jaws during the reciprocatory movement thereof, means for automatically releasing the fingers, and lapper mechanism 110 having two jaws movable toward and from each other and at right angles to the movement of the first-mentioned jaws and adapted to bend the metal binding 115 on the remaining side of the anvil.

4. In a box-making machine, the combina- 120 tion of a rectangular anvil, a cross-head, two jaws pivotally mounted on said cross-head and adapted to force metal binding about three sides of the anvil, cutting mech- 125 anism, means for initially holding the metal binding in said jaws, pivotally held fingers movable with the jaws and adapted to hold the binding in the jaws during the reciprocatory movement thereof, means for automatically releasing the fingers, and lapper mechanism 130 having two jaws movable toward and from each other and at right angles to the movement of the first-mentioned jaws.

and adapted to bend the metal binding on the remaining side of the anvil.

5. In a box-making machine, the combination of a substantially rectangular anvil, two supporting frame members, a reciprocatory cross-head movable between said members, levers pivotally mounted on said cross-head, adjustable guides for a part of said levers, a center member, jaws pivotally held to said center member and to said levers, springs normally forcing the jaws in one direction, means for initially holding the binding in the jaws, means for retaining the binding in the jaws during the reciprocatory movement of the cross-head, two oppositely movable jaws movable toward the anvil adapted to fold the ends of the binding about one part of the anvil and to cause the ends to overlap, and guides interposed between the first-mentioned jaws and the last-mentioned jaws to prevent the binding during the initial folding about the anvil being interfered with by the last-mentioned jaws.
6. In a box-making machine, the combination of a substantially rectangular anvil, a reciprocatory cross-head, levers pivotally mounted on said cross-head, stationary guides engaging a part of said levers, a center member, jaws pivotally held to said center member and to said levers, springs normally forcing the jaws in one direction tending to keep said jaws and the center member in alinement, stops for the center member and the cross-head, means for initially holding the binding in the jaws, means for retaining the binding in the jaws during the reciprocatory movement of the cross-head, two oppositely movable jaws movable toward the anvil adapted to fold the ends of the binding about one part of the anvil, and guides interposed between the first-mentioned jaws and the last-mentioned jaws to prevent the binding during the initial folding about the anvil being interfered with by the last-mentioned jaws, said guides having a part thereof overlying said last-mentioned jaws when in their normal position.
7. In a box-making machine, the combina-

tion of a substantially rectangular anvil, supporting means, a cross-head movable in said supporting means, levers pivotally mounted on said cross-head, guides engaging a part of said levers along which the levers travel, means coöperating with the levers to fold binding metal about a part of the anvil, and means for bending the binding about the rest of said anvil.

8. In a box-making machine, the combination of a substantially rectangular anvil, supporting frame members, a reciprocatory cross-head movable between said members, levers pivotally mounted on said cross-head, guides for a part of said levers, a center member, jaws pivotally held to said center member and to said levers, springs normally forcing the jaws in one direction, means for initially holding the binding in the jaws, means for retaining the binding in the jaws during the reciprocatory movement of the cross-head, means movable toward the anvil adapted to fold the ends of the binding about one part of the anvil and to cause the ends to overlap, and guides interposed between the first-mentioned jaws and the last-mentioned means.

9. In a box-making machine, the combination of a substantially rectangular anvil, supporting frame members, a cross-head movable between said members, levers pivotally mounted on said cross-head, guides for a part of said levers, a center member, jaws pivotally held to said center member and to said levers, springs normally forcing the jaws in one direction, a back stop adapted to engage the center member, means for initially holding the binding in the jaws, means for retaining the binding in the jaws during the reciprocatory movement of the cross-head, and two oppositely movable jaws movable toward the anvil adapted to fold the ends of the binding about one part of the anvil and to cause the ends to overlap.

This specification signed this 14th day of June, A. D. 1915.

CHARLES BURNHAM.
